MEASURING DEVICE FOR WORK PIECES

Eric M. Pohl, Southfield, Mich., assignor to Speedring Corporation, Warren, Mich., a corporation of Michigan

Filed Jan. 19, 1966, Ser. No. 683

Term of patent 14 years

(Cl. D52—6)

FIGURE 1 is a front elevational view of a measuring device for work pieces illustrating my new design;
FIGURE 2 is a side elevational view of the measuring device;

FIGURE 3 is a plan view of the measuring device; and
FIGURE 4 is a perspective view of the measuring device.

The rear of the measuring device is substantially flat and plain in appearance, and the left side is practically the same as the right side except that a dial indicator is attached to the housing generally opposite the knob and lever portion.

The dominant features of the design reside in the portions shown in full lines.

I claim:

The ornamental design for a measuring device for work pieces substantially as shown and described.
